UNITED STATES PATENT OFFICE.

WEBSTER C. BALL, OF CLEVELAND, OHIO.

DESIGN FOR A WATCH-PLATE.

SPECIFICATION forming part of Design No. 26,267, dated November 17, 1896.

Application filed September 8, 1896. Serial No. 605,194. Term of patent 14 years.

To all whom it may concern:

Be it known that I, WEBSTER C. BALL, a citizen of the United States, and a resident of Cleveland, county of Cuyahoga, and State 5 of Ohio, have invented and produced a new and original Design for Watch-Plates, of which the following is a specification, reference being had to the accompanying drawing, forming a part thereof, and which represents 10 a view of a watch-plate embodying my design.

The surface of the plate A is divided into a number of narrow concentric rings *a*, each of which rings is traversed by minute lines 15 *a'* in the form of overlapping curves, each ring containing two light and two dark surfaces, each such surface having its beginning at about the right-hand side of the termination

of one of the like surfaces in the ring inwardly contiguous to it. 20

The illustration shows the appearance of the watch-plate when the light falls upon it at an angle of forty-five degrees, the relative size of the light to the dark surfaces varying with the variation from said angle. 25

What I claim is—

The design for a watch-plate as herein shown and described.

In testimony that I claim the foregoing to be my invention I have hereunto set my hand 30 this 21st day of August, A. D. 1896.

WEBSTER C. BALL.
